UNITED STATES PATENT OFFICE.

PATRICK JOSEPH CONLEY, OF CANTON, OHIO.

BUILDING BLOCK.

Application filed July 30, 1925. Serial No. 47,094.

This invention relates to a block, formed of cement or similar material, designed for use in buildings, walls and the like, and the objects of the invention are to provide 5 a block which eliminates the use of studding and to which metal lath, plaster board, beaver board, or the like, may be directly connected, the outer surface of the block being arranged to form the outside wall of 10 the building, or if desired the block may be so constructed as to permit a stucco finish or the like to be applied thereto.

The above and other objects may be attained by molding the block from cement 15 or the like, and forming vertical ribs upon one or both faces thereof, reinforcing wires of substantially U shape being located through the block, the free ends thereof extending through said ribs and forming 20 attaching tangs by means of which metal lath, plaster board, beaver board or the like may be permanently connected to the blocks to form a wall of any desired finish.

An embodiment of the invention is illustrated in the accompanying drawing, in which,

Figure 1 is a plan sectional view of a portion of a wall constructed with the improved blocks showing metal lath and plaster connected thereto to provide the inside 30 wall of a building or the like;

Fig. 2, a detail perspective view of one of the improved blocks;

Fig. 3, a plan sectional view of one of the 35 blocks showing the reinforcing wires therein;

Fig. 4, an inside elevation of a portion of a wall built of the improved blocks, showing the relative location of the various wire 40 attaching tangs;

Fig. 5, a detail perspective view of the reinforcing wires showing their relative position, and

Fig. 6, a detail perspective view of one of the 45 blocks provided with vertical ribs upon its inner and outer surfaces.

Similar numerals of reference indicate corresponding parts throughout the drawing.

50 The block, indicated generally at 7, may be formed of cement or similar material, having the flat outer face 8 forming the outside of the wall, and the vertical ribs 9 and 10 at its center and side edges respectively, the ribs 10 being substantially half the thickness of the center rib 9, and the

noses or ends of said ribs being preferably rounded as shown at 11. The outer or body portion of the block may be of any desired thickness, depending upon the height of the 60 building to be constructed therefrom or the weight to be supported by the wall.

The block is reinforced by means of substantially U shaped wires 12 and 13, the wire 12 being located longitudinally through the block and at an angle, one end thereof extending through the lower portion of one of the end ribs 10, forming an attaching tang 14, while the other end thereof extends through the upper portion of the opposite 70 rib 10, forming a similar attaching tang 15. The wire 13 is vertically positioned through the center rib 9, and the ends thereof extend through the inner surface of said rib, forming the attaching tangs 16. 75

In constructing a wall of these blocks, the blocks are placed end to end with the ribs located vertically and upon the inside of the wall, and alternate courses of the blocks are staggered, thus producing spaced vertical 80 ribs running from top to bottom of the wall, as best shown in Fig. 4, the attaching tangs 14, 15 and 16 being substantially equally spaced through the said ribs.

Metal lath, as indicated at 17, may be 85 placed over the inside of the wall, thus constructed, the tangs 14, 15 and 16 extending through the mesh of said lath and being bent over at right angles, as shown in Fig. 1, firmly attaching the metal lath to the 90 wall, after which a coat of plaster or the like, as indicated at 18, may be placed upon the metal lath in the usual manner.

If desired, any form of builder board such as beaver board, plaster board or the 95 like, may be used instead of the metal lath and plaster, the board being placed against the inside of the wall, the tangs penetrating the same and being bent or clenched upon the board to retain the same in position. 100

Where it is desired to form a stucco or similar finish, upon the outside of the wall, each block may be provided with ribs 9^a and 10^a upon both its inner and outer surfaces, wires being located within the block and extended outward through both sides, forming the attaching tangs 14^a, 15^a and 16^a upon each side of the block. Metal lath may be connected to both the inner and outer surfaces of the wall, the usual plaster, as above 105 described, being placed upon the metal lath on the inside, while a coat of stucco or the 110

like may be placed upon the lath on the outside, or if desired, the inside of the wall may be finished with builder board as above described. This style of block, with the ribs upon two sides, may also be used for the purpose of constructing partition walls and the like.

From the above it will be seen that a fire-proof wall is provided, being formed of cement block, reinforced with wires, the ends of which form attaching tangs for connecting metal lath or any suitable form of builder board, no wood of any kind being required in the construction.

15 I claim:

1. A cement building block having spaced, vertical ribs at its center and ends, and U-shape, reinforcing wires located at angles to each other, the ends of one wire extend-

ing through the central rib and the ends 20 of the other wire extending through the end ribs at diagonally opposite corners of the block forming attaching tangs for attaching lath or the like.

2. A cement building block having spaced, 25 vertical ribs at its center and ends, the central rib being substantially twice the width of the end ribs, and U-shape, reinforcing wires located at angles to each other, the ends of one wire extending through the central rib and the ends of the other wire 30 extending through the end ribs at diagonally opposite corners of the block forming attaching tangs for attaching lath or the like.

In testimony that I claim the above, I 35 have hereunto subscribed my name.

PATRICK JOSEPH CONLEY.
